GAME CALL

Merrel C. Shoemaker, deceased, late of Eldon, Mo., by Gwendolyn O. Shoemaker, surviving spouse, Rte. 1,
Eldon, Mo. 65026

Filed June 8, 1972, Ser. No. 261,148

Term of patent 14 years

Int. Cl. D10—06; D29—99
U.S. Cl. D10—116

FIG. 1.

FIG. 2.

FIG. 3.

FIG. 4.

FIG. 5.

FIG. 6.

FIG. 1 is a view in perspective of a game call showing my design;

FIG. 2 is a side elevational view of the game call on a reduced scale;

FIG. 3 is an end elevational view as seen from the left of FIG. 2, on the scale of FIG. 1;

FIG. 4 is a bottom plan view of the game call on the scale of FIG. 2;

FIG. 5 is a top plan view of the game call on the scale of FIG. 1 with the striker member omitted for purposes of disclosure; and

FIG. 6 is an enlarged bottom plan view of the striker member, the remaining elements of the game call omitted for purposes of disclosure.

I claim:

The ornamental design for the game call, as shown and described.
